UNITED STATES PATENT OFFICE.

SAMUEL J. CAMPBELL, OF ST. LOUIS, MISSOURI.

SHOE SUPPORT AND STRETCHER.

Application filed November 28, 1924. Serial No. 752,657.

This invention relates to supports and stretchers especially adapted for use in connection with shoes.

Briefly stated, an important object is to provide a support and stretcher for shoes which may be applied to a door, a wall, or the like in such a manner that one or more shoes may be quickly and conveniently applied to the same so that the shape of the 10 shoes will be maintained when the same are not in use.

A further object of the invention is to provide a shoe support and stretcher which is neat in appearance, durable in use, and 15 cheap to manufacture.

Other objects and advantages will be apparent during the course of the following description.

In the accompanying drawing forming a 20 part of this application and in which like numerals are employed to designate like parts throughout the same,

Figure 1 is a perspective of the improved support and stretcher in use;

Figure 2 is a fragmentary elevation of the improved support and stretcher applied;

Figure 3 is a sectional view taken on line 3—3 of Figure 2.

In the drawing wherein for the purpose 30 of illustration is shown a preferred embodiment of the invention the numeral 5 designates a door to which the improved support and stretcher may be applied. However, it is to be distinctly understood that the invention forming the subject matter of this application may be applied to any suitable support without in any way departing from the spirit of the invention.

The improved shoe support and stretcher 40 comprises inner and outer attaching strips 6 and 7, respectively, having aligned openings for the reception of wood screws or other suitable fastening devices 8 by means of which the support is secured to the door.

Figure 1 plainly illustrates that the leaf 45 spring shanks 10 of a number of separate shoe trees are secured between the attaching strips 6 and 7 and are held in place by suitable fastening devices such as rivets 12.

Figure 2 plainly shows that the rivets 50 may be extended through the attaching strips 6 and 7 at opposite sides of the leaf springs 10 so as to cause the strips 6 and 7 to securely clamp the shanks.

The shanks 10 are provided at their upper 55 portions with heel engaging portions 14 which are somewhat oval shaped and which engage in the rear portions of shoes or slippers 16.

The lower portions of the leaf spring 60 shanks 10 are provided with somewhat pointed toe engaging portions 18 which fit in the forward portions of the shoes 16, all of which is fully illustrated in Figure 1.

The drawings illustrate that the leaf 65 spring shank 10 is curved outwardly from the attaching springs 6 and 7 and therefore spaces the shoe engaging portions or knobs 14 and 18 from the door or other support 5. In this manner the shoe may be conveniently and quickly attached to the tree and when 70 in place will be properly stretched and maintained in the proper shape for future use.

The article constructed in accordance with 75 this invention may be cheaply manufactured and may be applied to a door or the like without the exercise of unusual skill and without marring the appearance of the door. In fact, if it is found expedient to change 80 the location of the improved support the small holes left by the screws 8 may be easily filled or allowed to remain open as the screws naturally would not be very large and would leave very small and inconspicuous holes.

Having thus described the invention, what 85 is claimed is—

1. A shoe stretcher and support comprising a pair of strips having attaching means, a plurality of separate shoe trees having leaf 90 spring shanks confined between the strips and curved outwardly from the same, the major portions of the springs being free and the ends of the same being provided with toe and heel shoe engaging portions.

2. A shoe stretcher and support comprising 95 a pair of strips having attaching means, a plurality of separate shoe trees having leaf spring shanks having their intermediate portions confined between the strips and curved outwardly from the same, the ends 100 of the leaf spring shanks being provided with toe and heel shoe engaging portions, and means clamping the strips in engagement with the adjacent portions of said leaf spring shanks.

In testimony whereof I affix my signature.

SAMUEL J. CAMPBELL.
